(57) **CLAIM**

The ornamental design for a paint tray, as shown and described.

DESCRIPTION

FIG. 1 is a top front view of a paint tray showing my new design;

FIG. 2 is a front view of the paint tray of FIG. 1;

FIG. 3 is a rear view of the paint tray of FIG. 1;

FIG. 4 is a left side view of the paint tray of FIG. 1;

FIG. 5 is a right side view of the paint tray of FIG. 1;

FIG. 6 is a top view of the paint tray of FIG. 1;

FIG. 7 is a bottom view of the paint tray of FIG. 1; and,
FIG. 8 is a cross-section view of the paint tray of FIG. 1 taken along the line 8-8 in FIG. 6.

The stippled, dashed or broken lines where depicted illustrate portions of the paint tray but represent unclaimed subject matter and form no part of the claimed design.
